UNITED STATES PATENT OFFICE

131,133

DESIGN FOR A MILLING MACHINE OR THE LIKE

Glenn W. Tamm, Chicago, Ill., assignor to
George Gerfen Machine Co., Racine, Wis., a
corporation of Wisconsin

Application September 11, 1941, Serial No. 103,298

Term of patent 14 years

To all whom it may concern:

Be it known that I, Glenn W. Tamm, a citizen of the United States, residing at Chicago, in the county of Cook, and State of Illinois, have invented a new, original, and ornamental Design for a Milling Machine or the like, of which the following is a specification, reference being had to the accompanying drawings, forming part thereof.

In the drawings:

Fig. 1 is a front perspective view of a milling machine or the like showing my new design.

Fig. 2 is a rear perspective view thereof.

Fig. 3 is a front perspective view thereof showing the opposite side of the machine from that appearing in Fig. 1.

Fig. 4 is a fragmentary front perspective view of the upper portion of the machine, showing the cutter head at the front of the ram adjusted to a different position than that appearing in Figs. 1, 2 and 3.

What I claim is:

The ornamental design for a milling machine or the like, substantially as shown.

G. W. TAMMEN.
